HEAD BLOCK FOR AIR COOLED INTERNAL
COMBUSTION ENGINES

Charles S. Brown, Syracuse, N. Y.

Application February 15, 1932, Serial No. 592,975

9 Claims. (Cl. 123—171)

This invention relates to air cooled multicylinder, internal combustion engines, and has for its object, a head block construction wherein the heads are a unitary structure for manufacturing and machining purposes and yet have the required amount of individuality during the running operation of the engine, that the heads of air cooled engines must have because of the greater temperatures to which air cooled engines, and particularly the heads thereof, are subjected, compared with water cooled engines.

The invention consists in the novel features and in the combinations and constructions hereinafter set forth and claimed.

In describing this invention reference is had to the accompanying drawings in which like characters designate corresponding parts in all the views.

Figure 1 is a plan view of a head block for air cooled engines embodying my invention.

Figure 2 is a side elevation of parts seen in Figure 1.

Figure 3 is an enlarged, fragmentary, longitudinal, sectional view of the head.

Figure 4 is a plan view, similar to Figure 1, of another form of this invention.

Figure 5 is a fragmentary view on line 5—5, Figure 2.

Figures 6, 7, and 8, are views, similar to Figures 1, 2, and 3, of another embodiment of my invention.

Figure 9 is a fragmentary elevation of a cylinder and head block showing a head embodying this invention applied to air cooled engines where the cylinders are formed entirely separate and attached separately to the crank case.

Figure 10 is a fragmentary plan view of a head block embodying another form of the invention.

Figure 11 is an enlarged, fragmentary elevation of parts seen in Figure 10.

This head block is applicable to air cooled engines where the cylinders are en bloc, partly separated, or to engines where the cylinders are completely separated, as when the cylinders are bolted to the crank case individually. Heretofore, in air cooled engines, the cylinders have been mounted individually on the crank case, and each cylinder has an individual head entirely separated and disconnected from the head of the next cylinder.

In my pending applications, Serial Nos. 573,127, filed November 5, 1931 and 581,650 filed December 17, 1931, the latter now being Patent Number 1,915,119, I have shown a block air cooled engine with the cylinders partly separated, and others

flexibly connected, and the head of this application is applicable to either of the foregoing types.

This invention comprises a head block for air cooled engines partly separated into individual heads and provided with means, as relatively narrow tie pieces, connecting the heads, so that the individual heads, which are the hottest part of the entire cylinder construction, will be a unitary structure for the purpose of machining and assembling, and at the same time, have the required individuality during the operation of the engine, as in air cooled engines where the heads are entirely separated, the connecting pieces being rigid for holding the block as a unit during handling and machining, but also flexible when the block is heated under running conditions of the engine so that the heads react individually to the heat, and are not affected by the relative expansion of adjacent heads.

In Figures 1, 2 and 3, 1 designates the head block formed with a plurality of heads 2, the block being shown as comprising four heads. The block illustrated is provided with base and top slabs 3 and 4, and with heat radiating flanges 5, which also extend at 6 between the combustion chambers 7 of the heads. The heads are also provided with intake and exhaust ports 8 and 9, valve seats 10, and valve stem guide openings 11. The intake and exhaust passages open through the upper face of the top slab at 12 and 13 respectively, where they communicate with intake and exhaust manifolds, not shown, overlying the top slab. The valve stem guide openings 11 also open through the upper face of the top slab 4, in order that the valve stems may coat with valve mechanism. The base plate 3 is machined to fit the end face or faces of the cylinder block, not shown.

In the construction shown in Figures 1, 2, and 3, the block is cast, and machined with the individual heads integral and then, the individual heads are partly separated by cutting slots 14 which extend inwardly from one side of the block and terminate short of the other side, leaving a small connecting means, as tie pieces at 15 between the individual heads, the slots cutting part way through the flanges and the base and top slabs 3 and 4. The slots are usually so arranged that the connecting pieces 15 are on the intake, or cooler side of the head, and the intake openings 12 near the connecting pieces 15. Preferably, the block is provided with connecting means or tie pieces, as a bar or bars 16 extending crosswise of the open ends of the slots, that is, they are located on the exhaust, or hotter side of the head block, the bar being fixed to the in-

dividual heads at 17. The bar 16 is usually of a metal having a low coefficient of expansion and contraction, such as invar. In Figures 1, 2, and 3, the bars are secured to the heads, as by screws, and a heat insulating strip 18 may be interposed between the bars and the heads. The connecting pieces 15 and the bar 16 provide connecting means between the individual heads of less width, or less dimension than the block width and usually, 10 there are two bars 16, one located near the top of the block, and the other, near the bottom and preferably, these bars are connected to the slabs 3, 4, in contradistinction to the cooling flanges 5, or to the heads between the slabs. As the connecting, or tie pieces 15, are located on the cooler side of the engine, and the bar 16 is of invar, or other material having a low coefficient of expansion is located on the exhaust, or hotter side of the engine, the linear expansion and contraction 15 of any one head is not transferred to the next head.

In Figure 4, a different arrangement of slotting is shown, in which the individual heads 2 are separated by slots 19 extending between the heads 25 and terminating short of opposite sides of the block, so that small connecting or tie strips 20 remain at opposite ends of the slots 19, and either or both sides of the block are provided with short additional slots 21 on opposite sides of the end 30 portions of the slots 19. This arrangement of slots also prevents the transfer of any linear expansion of one head to the adjacent head by providing flexibility between the heads under running conditions, due to the small connecting or 35 tie pieces between the heads. The slots 19 are formed by cores during the casting of the block. The slots 21 are cut after the head is cast and machined.

In Figure 6, the individual heads are entirely 40 separated, except for the bars 30 fixed to opposite sides of the heads, these bars being fixed to the individual heads during the casting operation and serving to join the heads together as a unitary structure for machining purposes, and 45 also to provide flexibility under running conditions.

In Figure 9, the heads are similar to those shown in Figures 6 and 7, but connected by bars 160 on opposite sides thereof similar to the bars 50 16, Figures 1 and 2.

In Figures 10 and 11, the heads are similar to those shown in Figures 6 and 7, but connected by tie pieces of steel 40, on opposite sides of the block between the upper and lower slabs, the tie 55 pieces 40 having their ends embedded in the slabs or adjacent heads, or head sections, and provided with loops 41 between their ends and located in line with the spaces or slots between the heads, or head sections. The loops provide flexibility 60 between the heads when the heads are heated under running conditions.

Either the form of head shown in Figures 1, 2, 3, and 4, or the head shown in Figures 6, 7, 8, 9, 10 and 11, may be applied to a multicylinder 65 block, partly or entirely separated, as in my pending applications referred to, or to a multicylinder engine where the cylinders are entirely separated, as shown in Figure 9, and in any case, the heads are a unitary structure with the individual heads 70 separated from each other, insofar as expansion and contraction or distortion of any one head relative to the adjacent head is concerned.

What I claim is:—

1. A unitary head block for multicylinder internal combustion engines, the heads of the 75

block being partly separated from each other, and having flexible tie pieces integral with said heads to hold the heads rigid as a unit during handling and machining and permitting flexibility between heads so that the heads react individually under heated running conditions. 5

2. A head block for air cooled, multicylinder, internal combustion engines, the block being provided with intake and exhaust ports and passages, and valve seats and guides for the intake and exhaust valves, the block being formed with base and top slabs, and heat radiating flanges between the slabs, the block being partly separated into individual heads and each head including sections of the slabs, and tie pieces connecting the slab sections of adjacent heads. 10

3. A head block for air cooled, multicylinder, internal combustion engines, the block being provided with intake and exhaust ports and passages, and valve seats and guides for the intake and exhaust valves, the block being formed with base and top slabs, and heat radiating flanges between the slabs, the flanges of adjacent cylinders being separated, the slabs being provided with slots extending inwardly from one side of the block thereof separating the block into individual heads, said slots separating the heads between the slabs and the slots terminating short 20 of the other side of the block providing tie pieces, whereby the individual heads are partly connected. 25

4. A head block for air cooled, multicylinder, internal combustion engines, the block being provided with intake and exhaust ports and passages, and valve seats and guides for the intake and exhaust valves, the block being formed with base and top slabs, and heat radiating flanges between the slabs, the flanges of adjacent cylinders being separated, the slabs being provided with slots extending inwardly from one side of the block thereof separating the block into individual heads, said slots separating the heads between the slabs and the slots terminating short 30 of the other side of the block providing tie pieces, whereby the individual heads are partly connected. 35

5. A head block for air cooled, multicylinder, internal combustion engines, the block being provided with intake and exhaust ports and passages, and valve seats and guides for the intake and exhaust valves, the block being formed with base and top slabs, and heat radiating flanges 40 between the slabs, the flanges of adjacent cylinders being separated, the slabs being provided with slots extending inwardly from one side of the block thereof separating the block into individual heads, said slots separating the heads between the slabs and the slots terminating short 45 of the other side of the block providing tie pieces, whereby the individual heads are partly connected, the intake ports of adjacent heads being located near the closed ends of the slots. 50

5. A head block for air cooled, multicylinder, internal combustion engines, the block being provided with intake and exhaust ports and passages, and valve seats and guides for the intake and exhaust valves, the block being formed with base and top slabs, and heat radiating flanges 55 between the slabs, and being provided with slots extending inwardly from one side thereof partly separating the block into individual heads, the slots terminating short of the other side of the block providing tie pieces whereby the individual heads are partly connected, and tie pieces connected to the heads and extending lengthwise of the block and across the open ends of the slots. 60

6. A head block for multicylinder, internal combustion engines, the block being partially separated into individual heads, and tie pieces extending lengthwise of one side of the block and fixed to said heads to hold them in juxtaposition, said tie pieces holding the head rigid as a unit during handling and machining, and having flexibility to permit individual reaction of the heads under heated running conditions. 65

7. A head block for multicylinder, internal combustion engines, the block being partially separated into individual heads, tie pieces in- 70 75

tegral with the heads and being of less widthwise dimension than the heads, and other tie pieces extending lengthwise of the block and fixed to the heads to hold them in juxtaposition.

5 8. A head block for air cooled, multicylinder, internal combustion engines, the block being provided with intake and exhaust ports and passages, and valve seats and guides for the intake and exhaust valves, and being also provided 10 with base and top slabs, and heat radiating flanges between the slabs, the flanges of adjacent heads being separated, the slabs being partially separated by slots of less widthwise dimension that the slabs into sections for the individual heads, and tie pieces extending lengthwise 15

of the block and fixed to the heads for holding them in unitary relation and in juxtaposition to each other.

9. A unitary head block for multicylinder air cooled internal combustion engines in which air cooled cylinders are separated throughout their lengths and at their head ends, the head block being detachable from the cylinders and the heads of the block being partly separated from each other, and means integral with said heads connecting the heads together as a unit, said means being of less width than the widthwise dimension of the heads, whereby the greater part of two adjacent heads are separated.
